UNITED STATES PATENT OFFICE.

JOHN E. KETTEMAN, OF TOLEDO, OHIO.

PUSH-BUTTON SWITCH.

1,269,611.

Specification of Letters Patent. Patented June 18, 1918.

Application filed February 24, 1917. Serial No. 150,636.

To all whom it may concern:

Be it known that I, JOHN E. KETTEMAN, a citizen of the United States, and a resident of Toledo, in the county of Lucas and

5 State of Ohio, have invented a certain new and useful Push-Button Switch; and I do hereby declare the following to be a full, clear, and exact description of the invention, such as will enable others skilled in the art 10 to which it appertains to make and use the same, reference being had to the accompanying drawings, and to the characters of reference marked thereon, which form a part of this specification.

15 My invention relates to electric push-button switches, and it has for its object to provide a simple, efficient snap-switch that may be placed in or used in connection with electric circuits. It also has for its object

20 to provide a switch wherein the controlling elements may be reduced in number and may be made small in size in order that the switch may be incorporated with a pocket electric lamp for connecting the battery

25 with the electric lamp for purposes of flashing or for maintaining a closed circuit through the lamp. It also has for its object

to produce a switch which may be closed by the operation of a push-button and released

30 by a snap action which is controlled by an engaging member. Other advantages and features will appear from the description hereinafter appended and from the drawings forming a part hereof. To illustrate the

35 practicability of my invention I have selected a construction that contains the invention, it being understood that the structures containing the invention may partake of different forms. The construction selected is

40 illustrated in the accompanying drawings.

Figure 1 of the drawings is a perspective view of a lamp socket having in its base one form of switch containing my invention. Fig. 2 illustrates a sectional view through

45 the lamp socket. Fig. 3 is a top view of the lamp socket showing the cap removed. Fig. 4 is a sectional view taken on the line 4-4 indicated in Fig. 3. Fig. 5 is a side view of the push-button. Fig. 6 is a view of 50 a modified form of a construction containing the invention.

In the form of construction selected for purposes of illustration, 1 is a lamp socket, it being understood that the switch may be

contained in any other form of construction. 55 The switch is provided with a spring contact member 2. 3 is a coacting contact member which makes contact with the spring contact member 2 to close the circuit of the switch. In the form of the invention shown, 60 the contact member 3 is located on a rod 4, the contact member 3 forming a head connected to the rod 4. The rod 4 is connected with a push-button 5 of insulating material through a block 6. The rod 4, the block 6 65 and the push-button 5 move in a sleeve 7. A spring 8 is located intermediate the inwardly extending edge 9 of the sleeve 7 and the block 6. When the spring 8 is pushed inward by the pressure of the block 6 the compression of the spring 8 will cause the return of the block and consequently the return of the push-button 5. The push-button 5 may be pushed inward to cause contact 70 between the head 3 and the spring 2. If desired, the push-button 5 may be pushed inward and allowed to return, thereby causing the lamp to flash, that is, permit an intermittent current to pass through the circuit which is closed by the operation of the 75 switch.

Means, however, may be provided for holding the switch closed against the action of the compression spring 8. The sleeve 7 is located in a sleeve 10. The sleeve 10 is provided with a spring-dog 11 which is connected to the sleeve 10, or is formed of the same metal of which the sleeve 10 is formed. The head 3 is provided with a channel 12. The dog 11 has a slightly returned end 13 80 which may enter the channel 12 when the head 3 is moved far enough by pressure on the push-button 5. When the end 13 of the dog 11 enters the channel 12, releasement 85 of the push-button will cause the contact 3 to be held against the return action of the spring 8 and of the spring contact member 2. If, however, it is desired to release the switch from the dog 11, the push-button 5 may be pushed in a short distance so as to raise the 90 dog 11 out of or nearly out of the channel 12 and then upon sudden releasement of the push-button 5 the springs 8 and 2 will cause the head 3 to snap by the dog 11 and consequently open the switch. 95

Means may also be provided for positively engaging the switch so as to hold the contact members in closed relation. This may 100

be done by pushing the push-button 5 inward so that the head 3 will pass the spring dog 11 and so that the spring-dog 11 will drop behind the head 3 and engage the head. Thus the switch will be held closed. In order that the switch may be opened, means is provided for releasing the head 3 from engagement with the dog 11. The shell 10 is made elliptical in cross-section and is 10 pivotally connected to the shell 7. The shell 7 is provided with openings 14, while the shell 10 is provided with teats 15 which extend into the openings 14, which permit rotative movements of the shell 7 relative to the shell 10. By this means the shell 7 may be swung relative to the shell 10 and the head 3 will be swung away from the dog 11. In order to prevent the shell 7 from being moved away from the dog 11 by the action 20 of the dog 11 itself on the head 3, a spring 16 may be cut from the shell 10 which presses against the side of the shell 7 to hold the head 3 or rod 4 against the dog 11. To push the shell 7 about its pivot and away from the 25 dog 11 a push-button 17 may be located in the socket. It has a rod 18 that extends through an opening formed in the shell 10. The push-button 17 may be returned by a compression spring 19. When the push-button 30 17 is pressed the shell 7, together with the rod 4 and the head 3, is pushed from the dog 11, which permits the contacts 2 and 3 to be separated by the snap action of the spring 8 and the spring 2, and thus the circuit connected to the contact 2 and the ear 35 23 formed of a part of the metal of the shell 10 is opened.

In the modified form of construction containing the invention shown in Fig. 6, the 40 switch is supported on a wall plate 20 and is located in a block 21 of insulating material. The form of construction shown in Fig. 6 is a wall switch, and means is provided for swinging the shell 7 so as to release the head 3 from the dog 11 to open 45 the circuit formed by contact between the spring 2 and the head 3. The shell 7 is provided with a knob or head 22 through which the push-button 5 extends. The push- 50 button 5 may be operated in closing the switch by pushing the contact 3 against the contact 2 sufficiently to produce connection without engagement of the head 3, or it may be pushed inward sufficiently to be engaged 55 by the dog 11 entering the channel 12, or may be pushed in sufficiently for the dog 11 to slip in behind the head 3 to retain the switch in its closed position. When it is desired to open the switch the head 22 may be 60 moved laterally, thus swinging the shell 7 about its pivot and releasing the head 3 from engagement with the dog, whereupon the spring 8 will cause a return movement of the head 3 and thus open the circuit. The 65 switch may be opened by lateral pressure on

the push-button 5 without lateral pressure on the head 22, but inasmuch as there is liable to be friction between the finger and the push-button 5 upon the return movement of the push-button 5 by the operation of the spring 8, the quickness of the outward movement is apt to be reduced and arcing caused. A quick snap action opening the switch, however, may be obtained by proper lateral pressure and releasement of the push-button 5. Inasmuch, however, as the switch is for use by unskilled persons, the head 22 connected to the sleeve 7 to swing the sleeve 7 away from the dog 11 and thus leave the push-button free to move outward, is found 70 to be a preferable form of construction. 75

I claim:

1. In a push-button switch, the combination of a fixed contact, spring-pressed member having a coacting contact, a spring-dog 85 for engaging the spring-pressed member when the spring-pressed member is pushed to a certain point, means for causing the dog to release the spring-pressed member by further movement of the spring-pressed member and sudden releasement of the spring-pressed member. 90

2. In a push-button switch, the combination of a fixed contact, a spring-pressed member having coacting contact and a channel, a dog for entering the channel to engage the spring-pressed member when the spring-pressed member is pushed to a certain point, the spring-pressed member being released from the dog by further movement of the 100 spring-pressed member relative to the dog and sudden releasement of the spring-pressed member. 95

3. In a push-button switch, the combination of a spring-pressed member supported 105 for lateral and longitudinal movements, a dog for engaging the spring-pressed member when the spring-pressed member is moved longitudinally, and until the spring pressed member is moved laterally. 110

4. In a push-button switch, the combination of a spring-pressed member mounted for longitudinal and lateral movements and yieldingly held against said movements, a dog for engaging the member, and means 115 for releasing the spring-pressed member from the dog by lateral movements of the member.

5. In a push-button switch, the combination of a spring-pressed member, a shell, a second shell containing the spring-pressed member and pivotally supported in the first-named shell, a dog for engaging the spring-pressed member. 120

6. In a push-button switch, the combination of a spring-pressed member, a shell, a second shell containing the spring-pressed member and pivotally supported in the first-named shell, a dog for engaging the spring-pressed member and connected to the first- 125 130

named shell, and means operating on the shell for releasing the spring-pressed member from the dog.

7. In a push-button switch, the combination of a spring-pressed member having a channel, an elliptical shell, a second shell pivoted to the first-named shell and for containing the spring-pressed member, a dog located on the first-named shell for engaging the spring-pressed member, and means for moving the shell to release the spring-pressed member.

In testimony whereof, I have hereunto signed my name to this specification.

JOHN E. KETTEMAN.
